UNITED STATES PATENT OFFICE.

CHARLES W. ROBERTS, OF COHOES, NEW YORK, ASSIGNOR TO NORMAN W. FROST, OF SAME PLACE.

IMPROVEMENT IN SCREW-THREADING DEVICES.

Specification forming part of Letters Patent No. **158,314**, dated December 29, 1874; application filed August 15, 1874.

To all whom it may concern:

Be it known that I, CHARLES W. ROBERTS, of Cohoes, in the county of Albany and State of New York, have invented a new and useful Improvement in Machine for Cutting Screws on Tubing, &c., of which the following is a specification:

The object of this invention is to furnish ready and convenient means for cutting screws on gas-pipes, tubing of all kinds, rods, bolts, and similar articles; and consists in the construction and arrangement of parts herein-after described.

In the accompanying drawing, Figure 1 is a vertical section of Fig. 2 on the line *xx*. Fig. 2 is a section of Fig. 1, taken on the line *yy*.

Similar letters of reference indicate corresponding parts.

A is a bed-plate, which is fastened to a bench. *B* is the vise-plate, which is made adjustable on the bed *A*. *C* and *D* are the jaws of the vise. The lower jaw is stationary, and made in two parts, connected together by the bolt *E*. (See Fig. 1.) The upper jaw *D* is fastened to the sliding block *F*, which is attached to the vise-screw *G*. This jaw *D* works down between the two parts of the jaw *C*. Each of the jaws has a **V**-shaped opening, the sides of the **V** being serrated so as to effectually hold the tube within the angular openings, and keep it from turning. The vise-screw *G* works through the cross-bar *H* of the vise-plate. On each side of the vise-plate is a socket, *I*. *J* is an arm or brace, which is provided with two pins or bars, *K*. These bars enter the sockets *I*, and support the arm in a horizontal position, as seen in Fig. 1. *L* is the pinion. *M* is the die-wheel. *N* is the feed-screw. *O* are the dies, which are made fast in the face of the wheel *M*. The hub *P* of the die-wheel works onto the stationary screw-block *P*, as the wheel is turned, and

draws the dies *O* onto the tube. *R* is the tube. The die-wheel *M* is a cog-wheel, with which the pinion *L* engages. *S* is the pinion-shaft. *T* is the crank, by means of which the pinion is revolved. Instead of a crank fast and loose pulleys may be on the shaft for the employment of other motive power, as steam or water. This pinion is made long to allow the die-wheel to move in and out as it carries the dies on and off the tube. The tube is held stationary in the jaws of the vise, and the feed-block *N* is held stationary on the tube by the set-screw *U*. The arm *J* (which carries the pinion *L*) is raised and lowered, as may be desired and is held in position by the set-screws *V V*. This adjustment adapts the machine to different-sized tubes.

This machine is portable, and is used at great advantage by gas-fitters in fitting pipe to dwellings and buildings where the ordinary pipe has to be cut frequently to suit the various apartments. The machine may also be used for cutting bolts or screw-rods of various sizes with equal facility, and, with slight modifications, for cutting left-hand screw-threads.

Having thus described my invention, I claim as new and desire to secure by Letters Patent—

1. The combination, as herein described and shown, of the cutter-head *M*, having an internally screw-threaded hub, the hollow nut *N* for co-operating with said screw-hub, and attachable to the rod to be cut, the jaws *D C* for clamping the rod, and the long pinion *L*, for the purpose set forth.

2. The vise-frame *A*, having sockets *I*, in combination with the vertically-adjustable arm or pinion support *J*, having pins *K*, as and for the purpose specified.

CHARLES W. ROBERTS.
